US00D830064S

(12) **United States Design Patent** (10) Patent No.: **US D830,064 S**
(45) Date of Patent: ** *Oct. 9, 2018

(54) **GLUE BRUSH**

(71) Applicant: **Rockler Companies, Inc.**, Medina, MN (US)

(72) Inventors: **Steve Donald Krohmer**, Coon Rapids, MN (US); **Daniel L. Wenning**, Minneapolis, MN (US)

(73) Assignee: **Rockler Companies, Inc.**, Medina, MN (US)

(*) Notice: This patent is subject to a terminal disclaimer.

(**) Term: **15 Years**

(21) Appl. No.: **29/589,249**

(22) Filed: **Dec. 29, 2016**

Related U.S. Application Data

(60) Continuation of application No. 29/544,991, filed on Nov. 9, 2015, now Pat. No. Des. 776,939, which is a division of application No. 29/525,123, filed on Apr. 27, 2015, now Pat. No. Des. 744,241, which is a division of application No. 29/439,269, filed on Dec. 8, 2012, now Pat. No. Des. 738,628.

(57) **CLAIM**

The ornamental design for a glue brush, as shown and described.

DESCRIPTION

FIG. 1 is a perspective view of the glue brush.

FIG. 2 is a side elevation view thereof, the side elevation views being mirror images of one another.

FIG. 3 is a top plan view thereof.

FIG. 4 is a bottom plan view thereof.

FIG. 5 is a front elevation view thereof, looking into the bristles; and,

FIG. 6 is a rear elevation view thereof.

The dashed lines form no part of the claimed design.

1 Claim, 1 Drawing Sheet
